(57) **CLAIM**

The ornamental design for a coffee filter holder, as shown and described.

DESCRIPTION

FIG. 1 is a perspective view of a coffee filter holder showing my new design.

FIG. 2 is another perspective view of a coffee filter holder.

FIG. 3 is a front view of a coffee filter holder.

FIG. 4 is a rear view of a coffee filter holder.

FIG. 5 is a left side view of a coffee filter holder.

FIG. 6 is a right side view of a coffee filter holder.

FIG. 7 is a top view of a coffee filter holder; and,

FIG. 8 is a bottom view of a coffee filter holder.

The broken lines illustrate portions of the coffee filter holder that form no part of the claimed design.
